WINDOW GUARD

Michael T. Montefusco, Brooklyn, N. Y.

Application August 22, 1950, Serial No. 180,720

4. Claims. (Cl. 160—161)

1

This invention relates to new and useful improvements in window guards; and, more particularly, the aim is to provide a novel and valuable structure of collapsible type which, after being positioned in a window opening, as below the raised lower sash of a window having sliding sashes, may be expanded to fill in the space above the bottom sill and between the sides of the window frame so as then to act as a protective grating, as for the purpose of preventing a child from falling out of the window.

A particular object of the invention is to provide a window guard as above all the parts of which are permanently interconnected, yet one which, nevertheless, is so constructed that installation and expansion of the guard in a window frame opening may be quickly and easily accomplished.

A further specific object is to provide a window guard having the foregoing advantages, and one which, also, after installation and expansion as aforesaid, is locked so securely in place as to afford an insurance reliably to be depended on to defeat any attempts of a small child, accidentally or deliberately, and by strength and ingenuity, to move the guard toward collapse and consequently toward a condition to permit removal of the guard or any part of it from the window opening.

Another object of the invention is to provide a window guard which while having, among others, all the advantages already stated, shall be relatively inexpensive to manufacture, which shall be of rugged and enduring construction, and which at the same time shall be compactly collapsible for advantageous storage at the factory, warehouse or the like, during shipment, and in the home between uses.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an approved embodiment of the invention, in expanded condition.

Fig. 2 shows the guard of Fig. 1 in fully collapsed condition.

Fig. 3 is, on a reduced scale, an elevational inside view of a window and window frame, with the guard expanded and secured in the window opening.

2

Fig. 4 illustrates how the guard is partially collapsed preparatory to removing the same, this view fragmentarily showing said window installation, with the lower, inner sash now fully raised prior to and for permitting said partial collapse of the guard.

Fig. 5 is, on a scale enlarged over that of Figs. 3 and 4, a horizontal section taken on the line 5—5 of Fig. 3.

Fig. 6 is a fragmentary detail view, this being a vertical section taken on the line 6—6 of Fig. 5.

Fig. 7 is a view similar to Fig. 3 but illustrating the window guard constructed in accordance with a modification of the present invention.

Fig. 8 is an enlarged partial horizontal sectional view taken on the line 8—8 of Fig. 7.

Fig. 9 is a partial vertical sectional view taken on the line 9—9 of Fig. 8.

Fig. 10 is a perspective view per se of the slide member used on the right-hand side of the window guard.

Fig. 11 is an enlarged partial horizontal sectional view taken on the line 11—11 of Fig. 7.

Fig. 12 is a perspective view, per se, of the fixed member used on the left-hand side of the window guard.

The window guard, according to the first form of the present invention shown in Figs. 1 to 6, includes a plurality of elongate units so inter pivoted that when the guard is expanded as in Figs. 1, 3 and 5, a plurality of said units are horizontally extended at different levels and another plurality of said units are vertically extended at uniformly spaced intervals and crossingly of said horizontal units.

Referring now to the drawings more in detail, the new window guard is illustratively shown as having two of said horizontal units, the upper one of which includes a pair of sidewise aligned bars 10 and 11 of equal length, and the lower one of which includes a pair of sidewise aligned bars 12 and 14 of equal length; and as having five or more vertical slats 15.

All the bars 10, 11, 12, 14 and the slats 15 are shown as and may conveniently be of rectangular cross-section, and they may be made of any suitable material selected, as wood. The vertical slats 15 are all of square cross-section. The horizontal bars 10, 11, 12 and 14 are also all alike; except that, preferably, for a reason to become clear later, the bars 12 and 14 included in the lower horizontal unit are somewhat longer than the bars 10 and 11 included in the upper horizontal unit.

In the upper horizontal unit the bars 10 and 11

are spaced apart a distance equal to the width of a side of the slats 15; and in the lower horizontal unit the bars 12 and 14 are spaced apart the same distance. Between the bars 10 and 11 and also between the bars 12 and 14 the slats 15 are interposed; each of said slats being inter-pivoted at a rivet 16 with the bars 10 and 11 and at a rivet 17 with the bars 12 and 14. These rivets may well be the familiar steel rivets used as pivoting elements between various structural members of lawn swings and other outdoor furniture articles of collapsible nature.

Secured as by screws as indicated at 18 to each of the opposite ends of the upper horizontal unit 10—11, is a spring member 19. Each of these members 19 is plate-like in form, having across one end a line of teeth 20; this tooth carrying end of a spring member 19 being the end thereof projected beyond the end of the unit 10—11 to which that member 19 is secured. Said members 19 are highly resilient leaf springs, made of a non-ferrous metal, as, for example, spring brass, or, preferably, beryllium copper; since the latter, while like other non-ferrous metals non-rusting, is so exceptionally resilient that it has a modulus of elasticity several times that of the finest spring steel.

A standard window and window frame installation includes, as shown in Figs. 3, 4 and 5, a window frame 21 including a bottom sill 22, frame sides or jambs 23, an upper, outer sliding sash 24, and an inner, lower sliding sash 25. In each side frame is an inner stop 26, a guide strip 27, and an outer stop 28. Between the stops 26 and said strips 27 is the slideway for the lower sash 25, and between the stops 28 and said strips is the slideway for the upper sash.

To place and secure the guard in the window opening as shown in Fig. 3, all that is required is to raise the lower sash to its upward limit of movement to arrange the same as shown in Fig. 4 thus to increase to the maximum possible the window opening; then with the guard partially expanded as in Fig. 4 and in the window opening in line with the slideway for the lower sash 25 between the stops 26 and the guide strips 27, further to expand the guard until the same, reaching its maximum possible expansion as shown in Figs. 1 and 3, has each of the ends of its lower horizontal unit 12—14 thrust deep all the way into the space between the stop 26 and the guide strip 27 at that side of the window opening; and then, finally, to lower the lower sash 25 until its bottom comes to rest on the tops of the slats 15 as shown in Fig. 3.

Concurrently with the thrusting of the opposite ends of the lower horizontal unit including the bar 12 into said spaces between the stops 26 and the strips 27, the two leaf springs 19 become arranged in said spaces as indicated in Fig. 5 and as more clearly shown, in the case of one of said springs, in Fig. 6.

As will be noted from the last-named view, said spring along its projected portion has been forced to a curvature so as upwardly to approach at a fairly sharp angle the bottom of a slideway space between a stop 26 and a strip 27, with the teeth 20 of that spring ready to dig lightly into the window-frame side the instant there is manually applied to the guard an upthrust at a time when the horizontal units of the guard are restrained against free upward inclination to the oblique as in Fig. 4.

But the lower sash 25, when arranged as in Fig. 3, and hence resting on top of the slats 15,

adds by its down pressure a force tending to combat any such upward inclination of the horizontal units of the guard. It would only be a small child who would accidentally or deliberately be the source of a muscular effort to apply an upthrust to the guard when in place as in Fig. 3; but the strength of a small child would not be sufficient to overcome the down pressure of the lower sash 25 by way of an upthrust resulting from an upward inclination of one of the horizontal units of the guard. In this connection, it is to be noted that the effective application of such upthrust against the bottom of said sash would be far to one side of the sash, that is, at the top of the slat 15 at the extreme right or at the extreme left in Fig. 3.

The only way to remove the guard from the window opening is first to raise the lower sash 25 as in Fig. 4, and then partially collapse the guard as shown in that view. As has already been stated, when the guard is in place as in Fig. 3 the ends of the lower horizontal unit are trapped between the stops 26 and the guide strips 27, and the arched portions of the leaf springs 19 beyond the ends of the upper horizontal unit are also trapped between the said stops and the said strips.

If beryllium copper, for example, were used for the springs 19, their free but highly elastic flexibility would be such that the bars 10 and 11 could well be longer than as indicated in the drawing, say as long as the width of the window opening plus the height of a stop 26. Then, incidental to final placement of the guard in the window opening as in Fig. 4, and the attainment of equilibrium of tension as between the identical springs 19, the opposite ends of the upper horizontal unit 10—11 would each become inserted in the space between a stop 26 and the adjacent strip 27 to the extent of half the depth of such space.

Ordinarily, as will be understood, the teeth 20 of neither spring 19 will dig at all into a window-frame side; so there will be no difficulty in ever disengaging one spring 19 or the other from the adjacent window-frame side as a first preliminary, once the sash 25 has been raised all the way, to starting relative movements of the guard toward partial collapse thereof. Once even a very slight partial collapse of the guard is effected, the spring 19 other than the one first disengaged from the window frame may be equally easily or even more easily disengaged from the window frame.

In the construction of the modification of the invention shown in Figs. 7 to 12, the window guard differs only in the means for anchoring the guard in position beneath the lower edge of the lower sash 25 of the open window.

The anchoring means of this modification of the invention is comprised of small angle irons 30 and 31 which are secured permanently to the inner faces of the guide strips 27 by means of small screws 32. The angle irons 30 and 31 being secured to the guide strips 27 are out of the way and do not interfere with sliding movements of the sashes 24 and 25. The angle irons 30 and 31 are secured to the guide strips 27 to be spaced just slightly above the top edges of the sidewise aligned top bars 10 and 11, see Figs. 7 and 9.

The left-hand ends of the top bars 10 and 11 carry a fixed member 33 provided at its outer side with an outwardly projected lug 34 for engagement beneath the angle iron 30 for securing the

left end of the window guard against upward movement. The fixed member 33 is formed of sheet metal and has its sides 35 extended downward along the inner and outer faces of the bars 10 and 11 and bent therebeneath. The fixed member 33 is secured in position by means of a rivet 36 which is passed through aligned holes 37 formed in the depending sides of the member and through the bars 10 and 11.

At the right-hand ends, the top bars 10 and 11 carry a slidable member 38 provided at its outer side with an outwardly projected lug 39 for engagement beneath the angle iron 31 to releasably secure the right-hand end of the window guard in position against upward movement. The slidable member 38 is also formed of sheet metal and has depending sides 40 which extend along the outer faces of the bars 10 and 11. The sides 40 continue into inwardly directed bottom edge portions 41 engaged beneath the bottom edges of the bars 10 and 11 slidably retaining the slidable member 38 in position on the ends of the bars 10 and 11.

Resilient means is provided in connection with the slidable member 38 for retaining the lug 39 in engagement beneath the angle iron 31. That resilient means is comprised of a depending portion 42 on the top wall of the slidable member 38 which is located between the bars 10 and 11. The bottom end of that depending portion 42 is formed with an aperture 43 and one end of a contraction spring 44 is hooked into the aperture 43, see particularly Fig. 9. The other end of the contraction spring 44 is hooked over a pin 45 mounted across the outer ends of the bars 10 and 11.

Normally, the contraction spring 44 urges the slidable member 38 outward on the bars 10 and 11 so that its lug 39 will be retained in position beneath the angle iron 31 retaining the window guard operatively in position beneath the open inner sash 25. However, the slidable member 38 can be gripped in one's fingers and pulled against the action of the contraction spring 44 disengaging the lug 39 from beneath the angle iron 31. In that position the right-hand end of the window guard is free to be pivoted upward causing the lug 34 of the fixed member 33 to be withdrawn from beneath the angle iron 30 freeing the window guard to be completely removed from the window frame.

In all other respects the form of the invention illustrated in Figs. 7 to 12 is similar to that described in connection with Figs. 1 to 6 and like reference numerals are used throughout to identify like parts.

On the drawings, the window guards are illustrated mounted in position within the tracks for the inner or lower sash 25, but it is appreciated that the same can be mounted in the tracks for the outer or upper sash 24. In the latter position of the guards it is possible to effect a greater closing of the inner sash 25 with the guard still in position protecting the open portion of the window. In mounting the window guard illustrated in Figs. 7 to 12 in the tracks for the outer sash it is necessary that the guard be turned end for end so that the slidable member 38 is located at the left side of the window frame with the lugs 34 and 39 directed inward to be engaged beneath the angle irons 30 and 31.

While I have illustrated and described the preferred embodiments of my invention, it is to be understood that I do not limit myself to the precise constructions herein disclosed and the right

is reserved to all changes and modifications coming within the scope of the invention as defined in the appended claims.

Having thus described my invention, what I claim as new, and desire to secure by United States Letters Patent is:

1. In a collapsible window guard, a grating comprising a plurality of slats, and pairs of rigid elongate structures each pair forming an elongate unit, each of said units being pivotally connected to all of said slats, the points of such pivotal connections being uniformly spaced along said units and also uniformly spaced along said slats whereby the window guard may be expanded to dispose all said slats vertically and at the same time to dispose both elongate structures horizontally with one at a higher level and the other at a lower level, said points of said pivotal connections being uniformly spaced along both said elongate units thereby uniformly spacing said slats when the window guard is expanded as aforesaid, each of said elongate structures being of a length substantially equal to the lateral width of the window sash whereby when the window guard is placed in an opening in a sliding-sash window installation wherein said opening is of a prevised width and the guard is expanded as aforesaid below a raised sliding sash of said installation, the opposite end portions of both said elongate structures are projected into the slideway spaces for said raised sash, each of said slats being of the same length so that when the window guard is expanded as aforesaid the tops of the slats are horizontally aligned and consequently the bottoms of the slats are also horizontally aligned, and means on said elongate upper structure for resiliently retaining said structure in operative position beneath the sliding sash.

2. In a collapsible window guard, a grating comprising a plurality of slats, and pairs of elongate structures each pair forming an elongate unit, each of said units being pivotally connected to all of said slats, the points of such pivotal connections being uniformly spaced along said units and also uniformly spaced along said slats whereby the window guard may be expanded to dispose all said slats vertically and at the same time to dispose both elongate structures horizontally with one at a higher level and the other at a lower level, said points of said pivotal connections being uniformly spaced along both said elongate units thereby uniformly spacing said slats when the window guard is expanded as aforesaid, each of said elongate structures being of a length substantially equal to the lateral width of the window sash whereby, when the window guard is placed in an opening in a sliding-sash window installation wherein said opening is of a prevised width and the guard is expanded as aforesaid below a raised sliding sash of said installation, the opposite end portions of both said elongate structures are projected into the slideway spaces for said raised sash, angle irons mounted on the guide strips of the window installation at elevations slightly above the upper elongate unit, members mounted on the ends of said upper elongate unit, and lugs projecting from said members and engaging said angle irons retaining the window guard removably in position.

3. In a collapsible window guard, a grating comprising a plurality of slats, and pairs of elongate structures each pair forming an elongate unit, each of said units being pivotally connected to all of said slats, the points of such

pivotal connections being uniformly spaced along said units and also uniformly spaced along said slats whereby the window guard may be expanded to dispose all said slats vertically and at the same time to dispose both elongate structures horizontally with one at a higher level and the other at a lower level, said points of said pivotal connections being uniformly spaced along both said elongate units thereby uniformly spacing said slats when the window guard is expanded as aforesaid, each of said elongate structures being of a length substantially equal to the lateral width of the window sash whereby, when the window guard is placed in an opening in a sliding-sash window installation wherein said opening is of a prevised width and the guard is expanded as aforesaid below a raised sliding sash of said installation, the opposite end portions of both said elongate structures are projected into the slideway spaces for said raised sash, angle irons mounted on the guide strips of the window installation at elevations slightly above the upper elongate unit, members mounted on the ends of said upper elongate unit, and lugs projecting from said members and engaging said angle irons retaining the window guard removably in position, one of said members being fixed in position and the other being slidably mounted on the upper elongate unit to be movable relative thereto to disengage its lug from the associated angle iron freeing the window guard to be removed.

4. In a collapsible window guard, a grating comprising a plurality of slats, and pairs of elongate structures each pair forming an elongate unit, each of said units being pivotally connected to all of said slats, the points of such pivotal connections being uniformly spaced along said units and also uniformly spaced along said slats whereby the window guard may be expanded to dispose all said slats vertically and at the same time to dispose both elongate structures horizontally with one at a higher level and the other at a lower level, said points of said pivotal connections being uniformly spaced

5
